(57) **CLAIM**

The ornamental design for fabrication table, as shown.

DESCRIPTION

FIG. 1 is a top perspective view of the fabrication table showing the new design;

FIG. 2 is a left perspective view thereof;

FIG. 3 is a front perspective view thereof;

FIG. 4 is a bottom perspective view thereof;

FIG. 5 is a bottom/side perspective view thereof;

FIG. 6 is a top/front/side perspective view thereof;
and,

FIG. 7 is an alternate top/front/side perspective view thereof;
and,

FIG. 8 is an enlarged top/front/side partial perspective view thereof.

This table is designed with a work surface made up of modular tubes, connected to a base via adjustable hardware. The work surface is designed to fixture or hold parts to be worked or assembled.
